UNITED STATES PATENT OFFICE

LENNIE R. WINSLOW, OF MIAMI, FLORIDA

ELEVATOR

Application filed August 23, 1929. Serial No. 387,935.

This invention relates to elevators designed primarily for use in transporting passengers in large buildings.

Heretofore it has been necessary to provide one shaft for each cage or car and this has necessitated the utilization of a large area which might otherwise be employed for other purposes.

It is an object of the present invention to provide an elevator structure which requires two shafts only, one shaft being used by ascending cars while the other shaft is used by descending cars.

Another object is to provide an elevator structure in which a number of cars can follow each other in each shaft, a novel block system being used in connection therewith by means of which it becomes impossible for any car to approach another more than a predetermined distance.

A further object is to provide an elevator structure in which the cars are independently operated, each being under the control of an occupant.

A still further object is to provide simple and efficient transferring means whereby each car, on reaching the end of its shaft, while ascending or descending, will be transferred laterally to the adjoining end of the other shaft.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a vertical section through a portion of a building showing the present improvements installed.

Figure 2 is an enlarged section through the upper portion of the elevator structure showing the car transferring means, a position of

a car prior to entering said means being indicated by broken lines.

Figure 3 is a view similar to Figure 2 showing the positions of the parts after the car has been brought to the top of the "down" shaft.

Figure 4 is a horizontal section through a portion of a car and adjacent parts, showing the cooperating portions of the block system in one position.

Figure 5 is a view similar to Figure 4 showing the cooperating parts of the block system in another position.

Figure 6 is an end elevation of the upper transfer carriage, a car being shown therein and in the shaft therebelow in side elevation.

Figure 7 is a perspective view of one of the rods of the block system with its shifting fingers and tripping wing, the parts cooperating therewith being also shown.

Figure 8 is a perspective view of one of the rods of the block system adapted to be actuated by a transfer carriage.

Figure 9 is an enlarged section through the lower portion of the "down" shaft, the lower transfer carriage being shown in end elevation with a car therein and the storage mechanism below said carriage being also shown.

Figure 10 is a horizontal section showing the removable sections of the car carrying racks located in the storage room, the sections being shown by full lines in engagement with the traction gears of a car and, by broken lines, out of engagement with said gears.

Figure 11 is a perspective view of one of the shiftable sections of a rack.

Figure 12 is a bottom plan view of a car showing the controlling mechanism thereunder, the figure being partly in diagram.

Figure 13 is a section on line 13—13, Figure 12.

Figure 14 is a section on line 14—14, Figure 12.

Figure 15 is a section on line 15—15, Figure 12.

Figure 16 is an enlarged section on line 16—16, Figure 6.

Figure 17 is an enlarged section on line 17—17, Figure 9.

Figure 18 is a section through a portion of the upper transfer carriage showing its conductor rail and the moving contact in engagement therewith, the figure being partly in diagram.

Figure 19 is a horizontal section through the transfer carriage showing its driving mechanism in plan.

Figure 20 is a section on line 20-20, Figure 19.

Figure 21 is a front elevation of the controller on the elevator car.

Referring to the figures by characters of reference, A designates the "up" shaft of an elevator structure and B designates the "down" shaft, these shafts being arranged side by side and coextensive in length.

Arranged at the centers of opposite sides of each shaft are rails 1 each of which is in the form of a rack. The teeth on these racks all face in the same direction as will be apparent by referring, for example, to Figures 2 and 3. All of the rails terminate substantially flush with the topmost floor of the structure in which the apparatus is installed and also with the lowermost floor to be served by the apparatus. In the structure illustrated the several floors have been designated from *a* to *l* respectively, the uppermost floor being indicated at *l* while the lowermost floor is indicated at *a*.

Beneath the floor *a* is a storage room R and disposed in this room in alignment with the rails 1 are similar rails 2. It is preferred to have these rails 2 align solely with the rails in shaft B but, if desired, additional rails 2 can align with the rails 1 in shaft A. Each of the rails 2 has a short lower section 3 that normally aligns therewith and each section 3 has an arm 4 extending inwardly from its lower end portion.

The sections 3 are slidably mounted in guideways 5 and the arms 4 are pivotally connected to an actuating lever 6 at opposite sides of the fulcrum 7 thereof. By referring to Figure 10 it will be seen that when lever 6 is swung in one direction, the sections 3 will be moved laterally out of alignment with the rails 2. When lever 6 is moved in the opposite direction, however, these sections 3 will be brought back into alignment with the rails 2. A track 8 is extended between the shiftable sections 3 and is used for the purpose hereinafter explained.

The shafts A and B may be provided with suitably arranged guide rails 9 extending longitudinally thereof and within the back portion of each of these shafts is also located a conductor rail 10.

Located on the upper floor *l* is a track 11 that extends past the upper ends of the two shafts A and B and this track is adapted to be engaged by the supporting wheels 12 of a transfer carriage 13. The carriage is formed preferably of an open framework carrying

parallel rails 14 the lower portions of which are in the form of racks as shown at 15. These rails 14 are so positioned that when the transfer carriage is in one extreme position the rails 14 will align with the rails 1 in shaft A so that the rack portion 15 will constitute a continuation of the rack portions of rails 1.

Carriage 13 is adapted to be limited in its movement in one direction by a stop or bumper 16 and another stop or bumper 17 limits its movement in the opposite direction. When the carriage is in engagement with bumper 17 rails 14 align with the rails 1 in the shaft B and provide continuations 80 of the racks formed by the rails 1.

Mounted on the carriage 13 is an electric motor indicated generally at 18. This motor has diverging controlling levers 19, 19' and 20 secured to a shaft 93 which carries the movable contact or brush 94 of an electric switch 95 in the carriage. When the brush or contact is in one extreme position as shown at 96 in Figure 20, the switch is in "forward" position. The other extreme position 97 is "reverse" while the intermediate position 98 is the "stop" position of the switch. Lever 19 is connected by a link 21 to a cam 22 pivotally mounted at 23 within the carriage 13 close to one of the rails 14 in the carriage. One end of the link 21 is extended past lever 19 to form a push rod 24. Located above the bumper 17 in the path of this push rod is a stop 25 and another stop 26 is fixedly arranged in the path of lever 19' where it will be engaged by said lever when the transfer carriage reaches one limit of its movement as will be hereinafter explained. Located in the transfer carriage 13 is a conductor rail 27 adapted to align with and electrically engage one of the rails 10 when the carriage is brought to either of its extreme positions.

Other conductor rails 28 are arranged parallel with the path of movement of carriage 13 and adapted to be movably engaged by contact elements 29 movable with the carriage and electrically connected to the motor 18. The lead from one of these contact elements extends to the switch 95 and thence to the motor as shown at 99 in Figure 19. Motion is transmitted from the shaft of the motor 18 to one of the axles 100 of carriage 13 through a train of gears 101.

A tripping pin 30 is extended downwardly from one end portion of carriage 13 and disposed at one side of the path of the carriage is a lifting pin 31 mounted on one arm of a lever 32 the other arm of which extends into the shaft B close to the top thereof. This pin 31 and the arm of lever 32 that engages it may be yieldingly supported by a spring 33.

Arranged on the floor *a* is a track 34 that extends past the lower ends of shafts A and

B and is adapted to be engaged by the supporting wheels 35 of a transfer carriage 36. This carriage is similar in construction to the transfer carriage already described and is provided with parallel rails 37 in the form of racks adapted to be positioned between and in alinement with the rails 1 and 2 of shaft B when the carriage 36 is in one extreme position. When the carriage is in its other extreme position, the rails 37 will aline with the rails 1 in shaft A and also with the rails 2 thereunder, if they are employed.

Carriage 36, like carriage 13 is provided with a conductor rail 38 adapted to move into alinement with and to electrically engage one or the other of the rails 10. There is also provided a conductor rail 39 in the storage room R that alines with the rail 10 and is adapted to be electrically contacted by rail 38 when brought into alinement therewith.

Conductor rails 40 are arranged parallel with the path of movement of carriage 36 and are adapted to be movably engaged by contacts 41 mounted on the carriage and electrically connected to the motor 42 on the carriage, the same arrangement being used as on the carriage 13 heretofore described. This carriage 36 is limited in its movement by bumpers 43 and 44 and has diverging controller levers 45 and 46 provided with actuating mechanism such as that used in connection with the levers of motor 18 on the upper transfer carriage 13.

Arranged longitudinally within the shaft 35 are rotatable rods 47 arranged substantially parallel with each other and close together. The lowermost rod extends from floor b of the building structure upwardly through three floors. The second rod begins at floor c and extends upwardly through three floors. This arrangement is continued throughout the height of the shaft A.

In shaft B there are also provided rods 47 located close together and substantially parallel. These rods are arranged oppositely to those in shaft A, the first rod being extended downwardly from floor k to floor i, the second rod being extended from the floor j to the floor k, the third rod being extended downwardly from floor i to floor g, etc.

Each of the rods 47 in shaft A is provided at its lower end portion with a tripping wing 48 and extending from said rod at a distance from the wing approximately equal to the height of an elevator car is a shifting finger 49. Another shifting finger 50 is extended from the rod at its upper end. These fingers do not occupy the same plane but occupy planes diverging from the rod. This will be apparent by referring to Figures 4 and 5.

The uppermost rod 47 in shaft A has fingers 51 and 52 diverging therefrom and one or the other of these fingers is constantly in the path of the tripping pin 30 depending from carriage 13.

As before explained the rods 47 in shaft B are stepped downwardly from the upper end of the shaft instead of upwardly from the lower end. Extending from the upper end portion of each rod 47 in shaft B is a tripping wing 48 and this rod is also provided with tripping fingers 49 and 50 such as already described, the only difference being that the rods in shaft B are reversed as compared with the rods in shaft A. Likewise the lower end of the lowest rod in shaft B has diverging fingers 51 and 52 one or the other of which is always in the path of a tripping pin 53 extending upwardly from the transfer carriage 36.

The tripping wings and the fingers extending from the rods 47 in the two shafts A and B are normally positioned with the wings shifted laterally out of the paths of the elevator cars as hereinafter explained.

A plurality of elevator cars are used in the shafts and all of these cars are of like construction, each being adapted to follow the other at a predetermined distance upwardly in shaft A, laterally in carriage 13, downwardly in shaft B, and laterally in carriage 36 to the point of starting.

Each car, indicated at 54, has supporting wheels 55 adapted to engage the rails 8 when the car is lowered into the room R. A transverse shaft 56 extends under the car and is provided at its ends with traction gears 57 adapted to engage and travel along the toothed rails 1, 37, 2, and 15. These gears are held in mesh with the rails by angular guide plates 58 which extend partly around the rails as shown particularly in Figure 12.

An electric motor 59 is carried by each car and is adapted to transmit motion through gears 60 to shaft 56. The circuit 59' leading to this motor from the conductor rail 10 includes a stationary contact 61 and a movable contact 62. The movable contact is carried by a lever 63 fulcrumed as at 64 and extending between actuating lugs 65 that project from a slide 66.

A spring 67 is located in a housing 68 and bears at its ends against centering plungers 69 that project from the opposite ends of housing 68. These plungers bear against ears 70 and 71 depending from slide 66 and thus serve to hold said slide normally positioned where it will hold contact 62 centered on contact 61.

A bell crank lever 72 is fulcrumed on the bottom of the car so as to swing vertically and one arm of this lever is extended laterally beyond the car to form a tripping arm 73. This tripping arm is located where it will come against any one of the tripping wings 48 if moved out of normal position. When the tripping arm 73 is swung in either direction away from intermediate position, as shown by broken lines in Figure 13, it will cause bell crank 72 to shift slide 66 against

one of the plungers 69, thereby to compress spring 67 and move contact 62 off of contact 61. Obviously this will break the circuit to the motor 59 so that the car cannot proceed under its own power.

Secured to the shaft 56 is a brake wheel 74 around which is extended a brake band 75 the ends of which engage oppositely extending cranks 76 carried by a shaft 77. This shaft has a radial arm 78 to which is connected the slide 66. Thus it will be seen that when slide 66 is shifted in either direction out of normal position the two cranks 76 will be swung out of a vertical plane and act to draw the ends of the band 75 toward each other. Thus the band will be clamped on wheel 74.

Another brake wheel 79 is secured to the shaft 56 and extending therearound is a band 80 one end of which merges into an arm 81 in which is pivoted a lever 82. This lever has a short arm 83 connected by a link 84 to the other end of the band. The other arm of lever 82 is connected by a long link 85 to a hand-operated brake lever 86 and to a foot-operated brake lever 87. These levers 86 and 87 are located where they can be actuated readily by the person handling the controller 88. This controller, which includes a handle 88', can be of any desired construction and is used for regulating the flow of current to motor 59 when the circuit 59' is not otherwise interfered with. See Figure 12.

Mounted on the outside of each car 54 is a bracket 89 on the outer end of which is secured a rectangular cam 90 positioned where it will strike successively against the fingers 49 and 50 as it travels upwardly in shaft A and downwardly in shaft B. Extending from the upper portion of each car is a tripping pin 91 and at another point each car has a bell crank lever 92 constituting a trip which can swing upwardly but is limited in its downward movement.

As before explained a number of cars 54 are to be used in the shafts A and B. These are designed to follow one another upwardly in shaft A and downwardly in shaft B. As an upwardly moving car leaves floor 3, one edge of the cam 90 will come against finger 49 of the first rod 47 and deflect said finger laterally out of the path of the cam. This movement will also swing the tripping wing 48 inwardly to position beneath the car where it will remain until the car has ascended a predetermined distance whereupon the cam will come against finger 50 and swing it laterally. This will rotate rod 47 and swing the wing 48 out from under the car. With the rods stepped as explained heretofore and each rod extending through three stories, it will be apparent that as a car ascends three wings 48 will be brought successively to position beneath the car and thereafter, as the car continues to ascend, additional wings will be swung to position there-

under while the lower wings will be swung out of position. In other words three wings will always be positioned beneath an ascending car.

Each car is caused to move upwardly in the shaft A by the transmission of power from its motor 59 to the traction gears 57 which are caused to travel upwardly along the teeth of the rails 1. Each car can of course be stopped at any landing and when the current to the motor is shut off the car is held by the application of brake band 80 to wheel 79 through actuation of levers 86 or 87.

When an ascending car reaches the upper end of shaft A it will continue to travel upwardly along the rails 14 in the transfer carriage 13. As the bottom of the car and the wheels 55 suspended therefrom pass above the level of floor 3 the tripping bell crank 92 will come against cam 22 and swing it laterally to the position shown in Figure 2. Thus motion will be transmitted through link 21 to the controller levers 19 and 20 moving them to the positions shown in Figure 2. This will cause the motor 18 to be placed in circuit with the rails 28 and propel the transfer carriage from the position shown in Figure 2 to the position shown in Figure 3. Consequently the car in the carriage will be conveyed from above shaft A to position above shaft B. During this travel of the transfer carriage the car is held against downward movement by brake wheel 79 and band 80.

The starting of the transfer carriage with its load is automatic and as the carriage reaches the limit of its movement it will be stopped by bumper 17. Push rod 24 will come against the stop 25 and shift levers 19, 19' and 20 and the brush or contact 94 to intermediate or "off" position. With the parts thus located lever 20 is supported over pin 31 and the rails 14 are in alinement with the rails 1 in shaft B. The car 54 can now descend, such descent being controlled by the brake members 79 and 80 and the motor 59 and gears 57. As the car passes downwardly out of the transfer carriage 13, the stud or projection 91 strikes against one end of lever 32 and depresses it, causing the other end to push pin 31 upwardly. This pin will thrust against lever 20 and swing it and levers 19 and 19' and contact or brush 94 to positions for reversing the motor 18 and causing the carriage 13 to travel back to its initial position against bumper 16. As the carriage reaches this position lever 19' strikes the stop 26 and the contact 94 and levers 19 and 19' are shifted back to neutral or "off" position as indicated by broken lines in Figure 2 and these levers will thus remain until again actuated by strip 92 and cam 22.

When the transfer carriage 13 moves from the position shown in Figure 2 to the position shown in Figure 3, the pin 30 comes

against finger 51 and rotates the upper tripping wing 48 so as to bring it into active position within shaft A. When the transfer carriage 13 moves back to the position shown in Figure 2, the pin 30 will strike finger 52 and swing the tripping wing 48 out of active position.

When a descending car in shaft B passes each of the fingers 49 it swings a wing 48 to position above the car and these wings are successively moved into and out of active positions in the same way as those located in shaft A with the exception that the active wings are above the descending car and not below the car. The same cam 90 will act on the fingers in both shafts because the lower half is a duplicate of the upper half.

When each car reaches the lower end of shaft B, it will enter transfer carriage 36 and be conveyed automatically to the bottom of shaft A where the car can start its upward travel. The operation of carriage 36 is controlled in the same way as carriage 13. When the carriage moves away from and back to position under shaft B the pin 53 will move the lower wing 48 into and out of active position.

Where two or more cars are moving in the same direction in shaft A or B, it is essential that means be provided to prevent them from colliding. It is for this reason that the rods 47 and the means cooperating therewith have been provided. Should a car approach too closely to another car in advance thereof, the tripping arm 73 of the second car will come against the lower wing 48 still in the path thereof and which has not yet been shifted to inactive position by the first car. As soon as arm 73 is tripped the bell crank 72 will shift slide 66 to break the electrical connection between contacts 61 and 62. Consequently the motor of the second car will be de-energized. Slide 66, when thus actuated, will rotate crank shaft 77 so that the band 75 will be automatically applied to brake wheel 74, thus holding the car against further movement. The operator in the car thus stopped can throw the controller 88 to shut off the current and can apply the band 80 to wheel 79. After the first car has passed upwardly a sufficient distance to throw out the restraining wing 48, the second car can proceed, it being understood that spring 67 will restore the connection to the motor and release band 75.

As the movement of each transfer carriage away from the shaft from which a car is received results in the actuation of the uppermost wing 48, it will be apparent that a car cannot enter the space above the shaft A or below the shaft B until after the transfer carriage has returned to position to receive the car.

When it is not desired to use a car, as for example, after ordinary business hours when

traffic is light, said car can be lowered from the transfer carriage 36 along the rails 2 to the track 8. By then shifting lever 6 to the position shown by broken lines in Figure 10, sections 3 can be withdrawn from between guide plates 58 and gears 57. This will leave sufficient clearance to allow the car to travel along track 8, leaving enough space between rails 2 to receive another car. Thus all cars not in use can be stored in room R. When it is desired to return the cars to active service they can be elevated along rails 2 at the bottom of shaft A and passed through transfer carriage 36 into shaft A or they can be transferred by carriage 36 from shaft B to shaft A.

What is claimed is:

1. Elevator apparatus including an "up" shaft and a "down" shaft, transfer carriages movable across the upper and lower ends of the shafts respectively, a plurality of independently operated cars within the shafts and movable successively from the "up" shaft into the upper transfer carriage and from the "down" shaft into the lower transfer carriage, means controlled by each car on entering either carriage for moving the carriage from extreme position to the other, and means controlled by each car when leaving either transfer carriage for returning the carriage to car-receiving position.

2. Elevator apparatus including separate shafts, a plurality of cars movable upwardly in one of the shafts and downwardly in the other shaft, means for automatically transferring the cars horizontally from one end of one shaft to the other shaft, and means controlled by each car for rendering the next succeeding car inactive on arriving at a predetermined distance from the car in advance thereof.

3. Elevator apparatus including separate shafts, longitudinal rails therein constituting racks, transfer carriages movable across the respective ends of the shafts, rails in each carriage adapted to be brought into alignment with the rails in the shafts, a car movable in the shafts, motor-driven means carried by the car for engaging and travelling along the rails in the shafts and onto the rails in the transfer carriage in the path thereof, and means controlled by the car for automatically shifting each carriage to transfer the car therein from position at one end of one shaft to one end of the other shaft.

4. The combination with elevator shafts and a rail in each shaft constituting a rack extending longitudinally of the shaft, of cars movable in the shafts, a motor carried by each car, means actuated by each motor for engaging the rail to move the car longitudinally of the shaft, and means at the upper and lower ends respectively of the shafts for transferring the cars successively from one shaft to the other.

5. In an elevator structure the combination with separate shafts, of a plurality of cars movable longitudinally of the shafts, transfer carriages movable across the ends of the shafts, each of said carriages constituting means for receiving cars successively from one of the shafts, means controlled by each car on entering and leaving the carriage for automatically shifting said carriage to transfer the car from one shaft to the other and return the carriage to its initial position.

6. In an elevator structure the combination with separate shafts, of a plurality of cars movable independently longitudinally of the shafts, transfer carriages movable across the ends of the shafts, each carriage constituting means for receiving cars successively from one of the shafts, means controlled by each car on entering the carriage for actuating the carriage to transfer the car to the other shaft, and means controlled by the car when leaving the carriage for returning the carriage to its initial or car-receiving position.

7. In an elevator structure the combination with separate shafts, of a plurality of cars movable independently longitudinally of the shafts, transfer carriages movable across the ends of the shafts, each carriage constituting means for receiving cars successively from one of the shafts, means controlled by each car on entering the carriage for actuating the carriage to transfer the car to the other shaft, means controlled by the carriage for preventing a car from moving into the path of the carriage while the carriage is away from normal position, and means controlled by each car on entering and leaving the carriage for automatically shifting said carriage to transfer the car from one shaft to the other and to return the empty carriage to its initial position.

8. In elevator apparatus the combination with separate shafts, of independently operated cars movable upwardly in one shaft and downwardly in the other shaft, controlling means secured within each shaft, and means carried by each car for actuating said controlling means and limiting the approach of the next succeeding car.

9. In elevator apparatus the combination with separate shafts, of independently operated cars movable upwardly in one shaft and downwardly in the other shaft, and means controlled by each car for limiting the approach of the next succeeding car, said means including superposed tripping elements arranged in series extending longitudinally within the respective shafts and means actuated by each car for shifting said elements successively into and out of position back of the car as it is travelling upwardly or downwardly in the shafts.

10. In elevator apparatus the combination

with separate shafts, of independently operated cars movable upwardly in one shaft and downwardly in the other shaft, means controlled by each car for limiting the approach of the next succeeding car, said means including superposed tripping elements arranged in series extending longitudinally within the respective shafts and means actuated by each car for shifting said elements successively into and out of position back of the car as it is travelling upwardly or downwardly in the shafts, and means on each car for engagement with a tripping element in the path thereof for rendering said car inactive.

11. The combination with an elevator shaft and a plurality of independently operated cars movable in the same direction in the shaft, of means operated by each car for preventing collisions between cars, said means including superposed tripping elements movably mounted in the shaft, means controlled by the car for shifting said elements successively into and out of the path of the next succeeding car, and means on each car for engaging a tripping element to stop the car when within a predetermined distance from the next car in advance thereof.

12. In an elevator structure the combination with a shaft, of a plurality of cars independently movable one above the other in the same direction within the shaft, a series of superposed tripping elements in the shaft, means on each car for driving the same, a brake for said driving means carried by each car, means operated by each car for successively moving the tripping elements into active position following the movement of the car past said elements and for subsequently shifting said elements to inactive positions, and means carried by each car for automatically rendering the car inoperative and applying the brake when said car is brought into active relation with one of the tripping elements.

13. The combination with an elevator shaft and a plurality of independently movable cars adapted to travel in the same path and direction within the shaft, of longitudinally disposed rods arranged in stepped relation longitudinally of the shaft, a tripping element carried by each rod, tripping fingers extending from each rod, means carried by each car for successively engaging one finger of a rod to shift the tripping element to position back of the car and to engage the other finger of the rod to shift the element out of position back of the car, and means on each car for engaging the tripping element when in one position to stop the car automatically.

14. In an elevator structure the combination with an "up" shaft and a "down" shaft, there being a storage space below the shafts, of a transfer carriage movable between the shafts and the storage space, a plurality of

cars movable within the shafts and successively into the transfer carriage, means controlled by each car on entering the carriage to shift said carriage automatically and transfer the car from one shaft to the other, means controlled by each car on leaving the carriage for automatically returning the carriage to its initial position, and means for guiding a car between the carriage and the storage space.

15. The combination with an elevator shaft; rails therein constituting racks, a transfer carriage movable to position at one end of the shaft, and rails in the carriage constituting racks adapted to align with the shaft rails, of rails extending below the carriage and constituting racks, said rails being fixedly mounted and alining with the shaft rails, a car movable within the shaft, gears thereon engaging and movable along the rails in the shaft to the rails in the carriage and thence to the rails beneath the carriage, rack sections forming continuations of the rails beneath the carriage, wheels on the car, a track for engagement by the wheels when the gears are lowered into engagement with the rack sections, and means for shifting the rack sections to release the car therefrom for movement along the track.

20. 16. In elevator apparatus the combination with an "up" shaft and a "down" shaft, and a plurality of cars movable longitudinally within the shafts, transfer means at each end of the shafts for receiving cars, means controlled by the movement of each car into one transfer means from one shaft for moving said transfer means to bring the car to position across the other shaft, and means controlled by the car when leaving the transfer means for moving said transfer means back into its initial or car-receiving position.

25. 17. In elevator apparatus the combination with separate shafts, of independently operated cars movable upwardly in one shaft and downwardly in the other shaft, and means controlled by each car for limiting the approach of the next succeeding car, said means including a tripping element arranged in each shaft and means actuated by each car for shifting said element successively into and out of position back of the car as it is travelling upwardly or downwardly in the shafts.

30. 18. An elevator construction comprising, in combination, a plurality of elevator shafts, a plurality of elevator cars, a power unit for each car permitting independent operability of a plurality of elevator cars in each of said shafts, and means for transferring said elevator cars from one to the other of said shafts.

35. 19. An elevator construction comprising, in combination, an ascending shaft, a descending shaft, a plurality of elevator cars, power means for each car permitting inde-

pendent operability of a plurality of elevator cars in each of said shafts, and means for transferring said cars from one to the other of said shafts.

20. An elevator construction comprising, in combination, an ascending shaft, a descending shaft, a plurality of elevator cars, power means for each car permitting independent operability of a plurality of elevator cars in each of said shafts, means for transferring said cars from a position adjacent the top of said ascending shaft to a position adjacent the top of said descending shaft, and means for transferring said cars from a position adjacent the bottom of said descending shaft to a position adjacent the bottom of said ascending shaft.

21. An elevator construction comprising, in combination, a plurality of elevator shafts, a plurality of elevator cars, a power unit for each car permitting independent operability of a plurality of elevator cars in each of said shafts, means for transferring said elevator cars from one to the other of said shafts, and means for closing and opening electric circuits during said transferring operations.

22. An elevator construction comprising, in combination an ascending shaft, a descending shaft, a plurality of elevator cars, power means for each car permitting independent operability of a plurality of elevator cars in each of said shafts, means for transferring said cars from one to the other of said shafts, and means for closing and opening electric circuits during said transferring operations.

25. 23. An elevator construction comprising, in combination, an ascending shaft, a descending shaft, a plurality of elevator cars, power means for each car permitting independent operability of a plurality of elevator cars in each of said shafts, means for transferring said cars from a position adjacent the top of said ascending shaft to a position adjacent to the top of said descending shaft, means for transferring said cars from a position adjacent the bottom of said descending shaft to a position adjacent the bottom of said ascending shaft, and means for closing and opening electric circuits during said transferring operations.

In testimony that I claim the foregoing as my own, I have hereto affixed my signature.

LENNA R. WINSLOW.
